UNITED STATES PATENT OFFICE.

ARTHUR A. MILLER, OF KAPOWSIN, WASHINGTON.

BOTTLE-STOPPER.

1,111,228.

Specification of Letters Patent. Patented Sept. 22, 1914.

Application filed July 14, 1913. Serial No. 779,034.

To all whom it may concern:

Be it known that I, ARTHUR A. MILLER, a citizen of the United States, residing at Kapowsin, in the county of Pierce and State of Washington, have invented certain new and useful Improvements in Bottle-Stoppers; and I do declare the following to be a full, clear, and exact description of the invention, such as will enable others skilled in the art to which it appertains to make and use the same.

This invention relates to improvements in stoppers for bottles and similar containers.

One object of the invention is to provide a stopper of this character in the form of a hollow cone shaped body formed of paper or similar fabric and having a reinforcing means to hold the same in fluid-tight engagement with the mouth of the bottle.

Another object is to provide a bottle stopper of this character which will fully take the place of the usual cork stopper and which may be manufactured at a much less cost.

With these and other objects in view, the invention consists of certain novel features of construction and the combination and arrangement of parts as will be more fully described and claimed.

In the accompanying drawings: Figure 1 is a vertical section of the neck and mouth of a bottle showing my improved stopper applied thereto, the stopper being shown in side elevation; Fig. 2 is an enlarged central vertical section of the stopper; Fig. 3 is a horizontal section thereof taken on the line 3-3 of Fig. 2; Fig. 4 is a plan view of the paper blank from which the stopper is formed; Fig. 5 is a perspective view of the same showing the manner in which the stopper is formed; Fig. 6 is a similar view of the reinforcing member of the stopper illustrating the manner in which said member is formed.

In constructing my improved stopper, I provide a circular disk 1 of suitable diameter and which is preferably constructed of heavy wax paper, but which may be constructed of any suitable fabric. The disk 1 is slotted or cut inwardly from its outer edge to its center as shown at 2 after which, beginning with one of the slotted edges the paper is coiled or wound spirally into a hollow cone which forms the body 3 of the stopper. When the paper disk is thus rolled

or coiled the tip or pointed end thereof is turned back before the last lap is rolled as indicated at 4 in Fig. 5 of the drawings, said turned back point of the cone being covered by the last wrapping or lap of the paper. By thus turning back the point of the cone said point is strengthened and reinforced. After the paper has been entirely wound or coiled the free edge thereof may be securely fastened by a liquid proof cement or glue and the paper or fabric thus prevented from unwinding.

The cone shaped body of the stopper when constructed in the manner described is reinforced at its outer open end and said end prevented from collapsing by a resilient reinforcing element comprising a segmental strip 6 of metal of suitable length and width which is rolled or spirally coiled to a sufficient extent to be inserted into the open outer end of the body of the stopper and which owing to the resiliency of the metal will have a tendency to expand and to thus hold the outer sides of the cone in fluid tight engagement with the inner surface of the mouth of the bottle. The strip 6 has its outer surface serrated or roughened as shown at 7 to cause the same to form a tight engagement with the inner surface of the cone and to prevent the strip from slipping or working out of the upper end of the cone. The roughened or serrated surface 7 may if desired extend only a sufficient distance to cover the outer surface or coil of the strip. The upper edge of the outer portion of the strip is indented to form a series of outwardly extending projections or detents 8 which engage the upper inner edge of the cone and prevent the latter from being forced too far into the same. The strip is also preferably corrugated transversely as at 9, said corrugations preventing the strip from coiling up too much when the stopper is forced into the neck of the bottle. The corrugations 9 may extend throughout the entire length of the strip or as herein shown said corrugations may terminate at the inner end of the roughened and indented portion of the strip.

By providing a reinforcing element for the stopper as herein shown and described it will be seen that while the stopper may be forced into tight engagement with the mouth of the bottle and will be held in this position by said element, the latter will prevent the outer portion of the stopper from

collapsing or becoming dented or creased in such manner as to prevent the same from forming an absolutely fluid-tight closure for the bottle.

5 From the foregoing description taken in connection with the accompanying drawings, the construction and operation of the invention will be readily understood without requiring a more extended explanation.

10 Various changes in the form, proportion, and the minor details of construction may be resorted to without departing from the principle or sacrificing any of the advantages of the invention as claimed.

15 Having thus described my invention, what I claim is:

1. A bottle stopper formed from a fabric disk slit from its outer edge to its center and wound upon itself to form a cone shaped hollow body, the reduced end of which is turned back and covered by wrapping of the fabric to reinforce this end of the stopper, and a reinforcing element adapted to be

inserted in the open outer end of the stopper comprising a strip of resilient metal wound upon itself to form a circular coil, said strip having its outer surface roughened and provided on one edge with indentations adapted to form detents and corrugations formed transversely of said strip.

2. A bottle stopper formed from a disk of sheet material slit from its outer edge to its center and wound upon itself to form a cone-shaped hollow body, the reduced end of which has the edge of the material turned back upon itself and covered by wrapping the material whereby this end of the stopper is reinforced, and a reinforcing element inserted in the open outer end of the stopper.

35 In testimony whereof I have hereunto set my hand in presence of two subscribing witnesses.

ARTHUR A. MILLER.
